UNITED STATES PATENT OFFICE.

GEORGE WESTINGHOUSE, JR., OF PITTSBURG, PENNSYLVANIA.

MEANS FOR PREVENTING LEAKAGE IN GAS-MAINS.

SPECIFICATION forming part of Letters Patent No. 340,266, dated April 20, 1886.

Application filed February 3, 1886. Serial No. 190,686. (No model.)

To all whom it may concern:

Be it known that I, GEORGE WESTINGHOUSE, Jr., residing at Pittsburg, in the county of Allegheny and State of Pennsylvania, a citizen of the United States, have invented or discovered certain new and useful Improvements in Means for Preventing Leakage in Gas-Mains, of which improvements the following is a specification.

10 In the accompanying drawings, which make part of this specification, Figure 1, Sheet 1, is a transverse section through a gas-main, illustrating the application of my invention; Fig. 2, a plan or top view of the same; Fig. 3, Sheet 2, a transverse section through a high-pressure and a lower-pressure gas-main, illustrating a modification; and Fig. 4, a plan or top view of the same.

15 The object of my invention is to prevent the escape of gas at the joints of mains or conduits into the surrounding earth or air, and to effect the retention and utilization of such gas as may pass out of the main through leaks or interstices at its joints.

20 To this end my invention, generally stated, consists in the combination of a leakage-pipe leading from a chamber formed in or around a joint of the main to a delivery-pipe adapted to convey gas to a desired point of utilization, and an exhausting apparatus receiving gas 25 from said leakage-pipe and actuated by gas supplied from the main.

The improvements claimed are hereinafter fully set forth.

30 In the practice of my invention I provide, for the interception of leakage from the joints of a main or conduit through which natural or other gas is conveyed, chambers which inclose or communicate with the joints of the main, and which are so located and bounded as that any gas leaking from the main will be compelled to pass into them before escaping from the main. Instances of such chambers are illustrated in my Letters Patent Nos. 318,840, 318,841, 319,364, 319,365, and others, and their precise form and location is unimportant so long as they possess the capacity of intercepting leakage by being interposed between the inside of a main and the medium 45 which surrounds it. To prevent the escape of the gas which may find entrance to said chambers from the main into the surrounding

earth, I maintain a partial vacuum or pressure below that of the atmosphere in the chambers, and in order to collect and utilize the 55 gas from the chambers the maintenance of such low pressure is effected by the exhausting action of a current of gas under pressure discharged from the main through a pipe serving for purposes of normal delivery, the 60 leakage-gas exhausted from the chambers being thereby carried off with that, which is normally discharged to a desired point of utilization.

Referring to the drawings, which illustrate 65 constructions proper for the practice of my invention, the joints of the main 1, through which gas is conducted from a well or generator to be distributed for use, are provided with chambers 7, which may be either formed 70 within the joints, as shown, or may surround the same as external boxes or casings. The several chambers 7 of the main are connected by leakage-pipes 2 with a leakage-line, 3, of small diameter relatively to that of the main 75 1, and extending in corresponding direction therewith and adjacent thereto. An exhausting-pipe, 4, provided with a suitable check-valve, 5, which opens outwardly, leads from the leakage-line to an exhausting apparatus 80 adapted to induce a constant suction in the discharge, said apparatus being preferably an ejector consisting of an enlarged chamber, 6, into which is led a discharge-nozzle, 8, on the outer end of the pipe 4. A gas supply-pipe, 85 9, provided with a cock or valve, 10, leads from the main 1 into the ejector-chamber 6, in rear of the opening of the discharge-nozzle 8, and the chamber 6, after being reduced to form an annular passage of smaller diameter than 90 its main body around the opening of the discharge-nozzle, is thereafter enlarged and outwardly extended, and connected to a discharge-pipe, 11, leading to a furnace or other desired point of utilization, to which any gas that may 95 enter the chambers 7 and leakage-line 3 is conveyed, together with the gas delivered through the supply-pipe 9. The ejector and its connections may be inclosed in a box or chamber, 12, having an opening or man-hole 100 closed by a door, 13, so as to enable access to be had to the parts when beneath the ground for examination or repair, as may from time to time be necessary. It will be obvious that

a single ejector and delivery pipe will be adapted to serve only for a determined length of the main, and that therefore the same must be duplicated at suitable distances apart proportionately to the number of joints to which the improvement is applied.

In the modification shown in Figs. 3 and 4 the combined leakage and direct supply of gas, in lieu of being discharged from the ejector or into a delivery pipe leading directly to a point of utilization, as in the former case, passes into a chamber or reservoir, 14, from which it is led through a pipe, 15, provided with a check-valve, 16, into a low-pressure main, 17, through which it is conducted with the normal supply of said main to the points of distribution supplied thereby. As in the former case, the gas leaking from the joints of the main 1 is retained and utilized, a direct supply of gas from said main serving as the medium for the exhaustion of its joint-chambers 7. Any water which may pass into the joint-chambers will be collected in the reservoir 14, which may be provided with a suitable device for trapping the same off from time to time, as desired.

I claim herein as my invention—

1. The combination of a gas-main, a chamber formed in or around a joint thereof, a leakage-pipe leading from said chamber to a delivery-pipe adapted to convey gas to a point

of discharge for utilization, and an exhausting apparatus receiving gas from said leakage-pipe and actuated by gas supplied from the main, substantially as set forth.

35

2. The combination of a gas-main, a series of chambers, each formed in or around a joint thereof, leakage-pipes connecting said chambers with a leakage-line, an exhausting-pipe leading from said leakage-line to the discharge-nozzle of an ejector, a gas-supply pipe leading from the main into the ejector-chamber, which incloses said nozzle, and a delivery-pipe adapted to convey gas from the discharge end of said ejector-chamber to a point of discharge 40 for utilization, substantially as set forth.

40

3. The combination of a gas-main, a chamber formed in or around a joint thereof, a leakage-pipe leading from said chamber to an ejector-discharge-nozzle, a supply-pipe leading 45 from the main to an ejector-chamber inclosing said nozzle, and having its discharge end opening into a chamber or reservoir, and a delivery-pipe connecting said chamber with a low-pressure main, substantially as set forth.

45

In testimony whereof I have hereunto set my hand.

GEO. WESTINGHOUSE, JR.
